(57) **CLAIM**

The ornamental design for a wheel for a motor vehicle, as shown and described.

DESCRIPTION

FIG. 1 is a front perspective view of a wheel for a motor vehicle showing my design;

FIG. 2 is a front view of the wheel for a motor vehicle shown in FIG. 1;

FIG. 3 is a front perspective view of a wheel for a motor vehicle showing a second embodiment of my design;

FIG. 4 is a front view of the wheel for a motor vehicle shown in FIG. 3;

FIG. 5 is a front perspective view of a wheel for a motor vehicle showing a third embodiment of my design;

FIG. 6 is a front view of the wheel for a motor vehicle shown in FIG. 5;

FIG. 7 is a front perspective view of a wheel for a motor vehicle showing a fourth embodiment of my design; and, FIG. 8 is a front view of the wheel for a motor vehicle shown in FIG. 7.

The entire left side, right side, top, bottom and rear surfaces of all the embodiments of the wheel are not visible in their normal or intended use.
